TROUSERS HANGER

William G. Carlson, Providence, R. I.

Application October 5, 1934, Serial No. 747,002

3 Claims. (Cl. 223—68)

My invention relates to devices for supporting and stretching trousers.

My invention relates to that type of hangers whereby the trousers are suspended by engagement of their lower ends between resilient clamping members.

In prior structures of this type the gripping power of the clamping members required for supporting heavy trousers was so excessive that the cuffs or hemmed folds of the latter, embraced by said members, become distorted and otherwise injured; and an object of this invention is to insure perfect suspension of the trousers without excessive and deleterious compression of the cuffs or folds.

In prior art structures the entire width of the clamping arms was employed and required to solely perform the clamping function, which not only made it difficult to simultaneously maintain in elevated position and clamp the trousers, but resulted in leaving upwardly projecting portions of the cuffs or folds exposed. Further objects of this invention, therefore, are to perform the operation of interengaging the trousers with the clamping members automatically by utilizing the influence of gravity combined with vertical guiding and compressing means; and to shield the upwardly extending cuffs or hemmed folds by guarding means.

As the utilization of gravity in engaging the trousers with my device requires an initial elevation of the trouser cuff or fold portions to such a height that the leg portions of the trousers be first presented to the flaring ends of the clamping members, an additional object of my invention is to provide means particularly suited to engagement with the leg portions of the trousers for initially guiding the latter horizontally between the clamping members.

Still further objects of my invention are strength, simplicity and inexpensiveness of construction, and speed and facility of operation.

With the above and other advantageous features and objects in view, my invention consists of a novel construction and arrangement of parts more fully disclosed in the detailed description following, in conjunction with the accompanying drawing, and more specifically defined in the appended claims.

In the drawing,

Figures 1, 2 and 3 are a side elevation, and a top plan view, and front end elevation respectively of my novel trousers hanger, and

Figure 4, a section of the same on line 4—4 of Figure 2.

Similar reference characters indicate similar parts throughout the views.

My device is preferably composed of thin resilient metal throughout, and comprises a vertical attaching plate 7 provided in its top and bottom portion with perforations 10 and 11 respectively for the reception of attaching screws.

Two forwardly or horizontally directed supporting plates 13 are brazed or welded at their inner ends to the lateral edges of the attaching plate intermediate the perforations.

The supporting plates, interspaced, as at 14, slightly and gradually converge longitudinally toward each other as they recede from the attaching plate to enhance the resiliency of the supporting plates.

The plates 13 are of a length to equal or exceed the width of a trouser cuff, and have longitudinally disposed guide and guard portions 15 which are transversely inwardly inclined in a downward direction, and merge at their lower ends in longitudinally disposed inwardly projecting horizontal shoulder portions 16 extending beyond the planes of the guard portions, integral with the tops of depending longitudinally disposed plane or flanged bearing portions 17, each disposed at an angle to its respective guard portion.

The outer ends of the plates 13 comprise laterally projecting and flaring upper ear portions 19 extending from the top nearly to the bottom of the plates 13, and laterally flaring lower ear portions 20 projecting forwardly beyond the portions 19.

Upon the upper edge of one of the plates 13 is an upwardly projecting attaching lug 21 provided with spaced holes 22 for the reception of attaching screws.

In using my device the trousers to be engaged are manually grasped by the cuffs or the folded extremities and presented edgewise to the front end of the device with the cuffs or folds elevated to the horizontal plane of the upper part of the guard portions 15 of the supporting plates or higher, during which movement the ear portions 20 are convenient to engage the leg portions of the trousers preparatory to the next movement, which consists in moving the trousers, still in elevated position, in a horizontal line along through the space 14 to a point near the plate 7 with the ear portions 19 assisting in guiding the cuffs if they happen to have any portion within the horizontal plane of the plate portions 15. At the end of this movement the operator loosens his grasp and the trousers slip

downwardly by gravitation to final engaged position, during which movement the plate portions 15 guide and lightly compress the cuffs until their lower edges abut against and are stopped by the shoulder portions 16 of the plates, whereupon the bearing portions 17 of the plates embrace the legs of the trousers immediately below the cuffs and assist by their resiliency the shoulder portions 16 and guard portions 15 in supporting the trousers.

Usually the plate 7 is solely used for attaching purposes, but the lug 21 may also be used when the hanger is mounted in a corner of a room.

The described structure thus permits a certain speedy and semi-automatic insertion of the trousers into my device, involving the use of a single hand only in the operation, and distributing the strain upon the engaged portions of the trousers rather than concentrating it wholly on the cuffs or folds.

Furthermore the plate portions 15 completely guard the cuffs throughout their lengths and widths, and guide the latter vertically as the trousers descend into engaged position by gravity.

The described structure thus permits the operator by a speedy continuous movement, which may be performed by one hand only, to lift the trousers to the elevated position and swing them horizontally to a position where they are released and automatically drop into final suspended position, where the strain is distributed over both the trousers legs and the cuffs, rather than concentrated upon the latter. Furthermore the plate portions 15 completely guard the cuffs throughout their lengths and widths, and guide the latter vertically as the trousers descend into position by gravity.

I claim:—

1. A trousers hanger comprising a vertical attaching plate, and two resilient cooperating supporting plates having corresponding upwardly extending end edges thereof at one end of the

hanger permanently fixed to the face of the attaching plate and transversely inclined so as to converge downwardly to receive trouser cuffs therebetween, the ends of the supporting plates at the opposite end of the hanger being spaced apart for the lateral insertion of the trousers therebetween, said plates being of substantial width to guard the cuffs throughout their width.

2. A trousers hanger comprising a vertical attaching plate, and two resilient cooperating supporting plates having corresponding upwardly extending end edges thereof at one end of the hanger permanently fixed to the face of the attaching plate and transversely inclined so as to converge downwardly to receive trouser cuffs therebetween, said supporting plates having the inner sides thereof approximately concave providing longitudinal shoulder portions for receiving and supporting the trouser cuffs, the ends of the supporting plates at the opposite end of the hanger being spaced apart for the lateral insertion of the trousers therebetween, said supporting plates being of substantial width to guard the cuffs throughout their width.

3. A trousers hanger comprising a vertical attaching plate having perforations adapted to receive attaching screws, and two resilient cooperating supporting plates having corresponding upwardly extending end edges thereof at one end of the hanger permanently fixed to the face of the attaching plate and transversely inclined so as to converge downwardly to receive trouser cuffs therebetween, said supporting plates having the inner sides thereof approximately concave providing longitudinal shoulder portions for receiving and supporting the trouser cuffs, the ends of the supporting plates at the opposite end of the hanger being spaced apart and having laterally projecting flaring terminal ear portions for the lateral insertion of the trousers therebetween, said supporting plates being of substantial width to guard the cuffs throughout their width.

WILLIAM G. CARLSON.
